VACUUM CLEANER

Gustaf Einar Lofgren, Riverside, Conn., assignor
to Electrolux Corporation, Dover, Del., a corpo-
ration of Delaware

Application March 12, 1935, Serial No. 10,620

12 Claims. (Cl. 183—37)

My invention relates to vacuum cleaners and more particularly to vacuum cleaners of the enclosed bag type.

One of the objects of my invention is to provide 5 a vacuum cleaner of this type in which the bag may be more readily removed for emptying than has been the case heretofore. In the past, cleaners of this type having a casing adapted to be supported horizontally upon a horizontal surface 10 have been formed with an opening in a vertical plane through which the bag is removed. The open mouth of the bag is secured in this opening, and in order to remove the bag when partially filled with dirt, it has been convenient to stand 15 the cleaner on end in order that the dirt will not fall out when the cleaner is opened. In order to render this unnecessary, the cleaner in accordance with the present invention is formed with an opening for withdrawal of the dust bag located 20 in an inclined plane. Thus, the advantages of a horizontal construction are retained, and it is also convenient to remove the bag without first standing the cleaner on end.

The inclined dust bag opening has a further 25 advantage. It has heretofore been proposed to employ a dust bag which is longer than the available space within the cleaner casing in which it is received. Such a bag has, of course, a greater wall surface than one of equal or shorter length 30 than the space, and consequently offers less resistance to the passage of air. Necessarily, the walls of the bag are folded in order that it may be received in the smaller space and difficulties have been experienced in properly inserting the 35 bag due to the fact that most of the folds are apt to occur adjacent to the mouth of the bag and hence tend to block the passage of dust laden air into the bag. Even if the fan is operating during insertion of the bag, and hence producing 40 a suction effect tending to draw the bag into the space, this tendency will cease as soon as the closed end of the bag strikes the end of the space. Thereafter, the suction simply tends to expand 45 the bag and presses the folds, which are formed adjacent to the open end of the bag by the operator forcing this end into the space, against the sides of the space. I have determined, however, that if the mouth of the bag is held in a position inclined with respect to the lengthwise extent 50 of the space, as it is in a cleaner in accordance with the present invention due to the inclination of the dust bag opening, the tendency of the air flow to expand the bag has the effect of preventing the formation of folds adjacent to the mouth 55 of the bag, where the axis of the bag curves from

an inclined to a horizontal position, and causes the folds to be distributed more towards the closed end of the bag. Consequently, the inclined opening aids in the proper insertion of the long bag.

Another object of the invention is to reduce 5 the noise produced by the air discharged from the cleaner. To accomplish this, I cause the air to pass through a comparatively long passage after leaving the fan and to be discharged to the atmosphere through a plurality of openings, rather than through a single opening. Thus 10 the noise of the fan is deadened before the air is discharged from the cleaner and the roar produced by the rapid flow of air through a single opening is greatly reduced.

It is desirable that vacuum cleaners should be available for blowing purposes, as well as for their normal use as suction cleaners, and one of the objects of my invention is to provide connections 15 for a hose for both blowing and suction purposes at the same end of the vacuum cleaner.

A further object of my invention is the provision of a casing for a vacuum cleaner, particularly of the enclosed bag type, including two stampings, preferably an upper and a lower one. 25 Heretofore, casings for vacuum cleaners of this type have been cylindrical with an opening at either end, thus necessitating detachment and removal of the interior parts if access to them becomes necessary for purposes of repair or so forth. A two-piece casing, on the other hand, makes it possible to secure the interior parts to either of the stampings, and thus access thereto is possible by merely removing the other stamping. The original assembly of the device is also 30 facilitated inasmuch as the interior parts may be secured to one stamping before the other stamping is secured in place.

A casing made in this manner has many other advantages, some of the more important of which 40 will be mentioned. In the event of injury to one piece, only that piece need be replaced, thus reducing the cost of repairs. In this connection also, if the interior parts are secured to the undamaged stamping, the injured stamping may 45 be replaced without disturbing them. This will usually be the case if the interior parts are secured to the lower stamping, as shown in this application, inasmuch as the upper stamping is the one more apt to be injured. With a casing 50 comprising two stampings, one or both ends of the casing may be integral with these stampings, rather than separate pieces, as is necessary with a cylindrical casing, thus making a cheaper construction while eliminating opportunities for 55

leaks. Stampings may be of most any desired shape, thus making possible a wide latitude in the design of the casing so that it may best serve its intended purposes. For instance, reinforcing 5 ribs may be stamped directly in the casing. Also, the joint between the two stampings may be made air-tight, without soldering or riveting, by the use of a strip of packing material, such as rubber. The suction produced within the casing exerts a 10 large force tending to draw the abutting edges of the stampings together, and thus effects a tight seal, regardless of whatever other means are employed to fasten the parts together. Other advantages of this type of casing will be apparent 15 from description contained hereinafter.

Another object of my invention is to provide means whereby the plurality of outlet openings above referred to are closed when a hose is attached to the blowing opening, this means also 20 serving to close the hose connection blowing opening when no hose is connected.

Further objects and advantages of my invention will be apparent from the following description taken in connection with the accompanying 25 drawings forming a part of this specification and of which:

Fig. 1 is a side view of a vacuum cleaner in accordance with my invention;

Fig. 2 is a front view of the device shown in 30 Fig. 1;

Fig. 3 is a rear view of the device shown in Fig. 1;

Fig. 4 is a cross-sectional view taken on the line 4—4 of Fig. 1;

Fig. 5 is a cross-sectional view taken on the line 5—5 of Fig. 2;

Fig. 6 is a cross-sectional view taken on the line 6—6 of Fig. 5;

Fig. 7 is a cross-sectional view taken on the 40 line 7—7 of Fig. 5;

Fig. 8 is a cross-sectional view on an enlarged scale taken on the line 8—8 of Fig. 7;

Fig. 9 is a cross-sectional view on a similar scale taken on the line 9—9 of Fig. 7;

Fig. 10 is a cross-sectional view of a portion of the cleaner as shown in Fig. 5, but with a hose connected in position for blowing;

Fig. 11 is a perspective view of a part of the vacuum cleaner shown in the preceding figures;

Fig. 12 is a cross-sectional view on an enlarged scale showing the dust indicator;

Fig. 13 is a cross-sectional view taken on the line 13—13 of Fig. 12; and

Fig. 14 is a cross-sectional view taken on the 55 line 14—14 of Fig. 13.

Referring to the drawings, reference character 10 designates generally a hollow casing made of metal or other rigid sheet material. Casing 10 comprises an upper part or shell 11 and a lower 60 part or shell 12. If the casing is made of sheet metal the parts are preferably formed by stamping.

Lower part 12 is clearly shown in Fig. 11. Secured within part 12, as by welding, riveting or 65 the like, is a U-shaped channel member 13, which serves as a motor support. The upper horizontal edge of part 12 is formed with a V-shaped groove 14 adapted to receive a bead 15 of rubber or other resilient material. Bead 15 is formed 70 with a dove-tailed portion 16, (Fig. 6) and the lower horizontal edge of upper part 11 is stamped to form an edge 17 which extends into the upper groove formed by the dovetail. Bead 15 serves the dual purpose of providing an air-tight seal 75 between the upper and lower parts and of pro-

viding a bumper or guard around the cleaner casing to prevent the marring of furniture with which the casing accidentally may come in contact. Upper part 11 of the casing is secured to channel member 13 by means of a plurality of 5 screws or the like 18, and is thus held rigidly with respect to the lower part 12.

The forward part of the casing comprises a casting 19 into which are secured, as by screws 23, the forward ends of both the upper and lower 10 parts 11 and 12, respectively. Casting 19 is formed with a large circular opening 20 located in an inclined plane, as is clearly shown particularly in Figs. 5 and 12. A cylindrical wall 21 (Fig. 7) extends rearwardly from the opening 15 20 to the rear of casting 19. The casting is formed with an intermediate transverse wall 22, which extends across the entire casting below the opening 20. A cylindrical inner casing 25 is positioned within casing 10, and is joined to the 20 rear end of cylindrical part 21 of casting 19. Cylindrical part 21 and inner casing 25 provide a space within which is positioned a dust bag 26. The length of bag 26 is preferably somewhat greater than the space into which it is inserted, 25 so as to obtain the benefits of an increased wall surface. When in place, the walls of the dust bag are folded, as shown in Fig. 5. A cage 27 made of wire mesh or perforated plate may be located within inner casing 25 in order to space 30 the dust bag from the casing. This aids the passage of air through the walls of the dust bag. The forward open end of the dust bag is secured to a ring 28 having an outwardly extending flange 29 (Fig. 12). A packing ring 30 is secured over 35 the edge of flange 29 and the flange and packing ring are adapted to be clamped between the forward face of casting 19 and a cover member 31, which is secured in place by two or more spring clips 32. Cover member 31 is formed with a 40 threaded central opening 35 which is adapted to receive the threaded end of a hose 36.

Channel member 13 is provided with a plurality of inwardly extending lugs 37, which are preferably made of a phenol condensation product or other electric insulating material. An electric motor 38 is supported from lugs 37 by means of pins 39 extending through holes in the lugs 37 and in lugs 40 formed on the motor. Pins 39 may be surrounded with coil springs in 50 order to give the motor a resilient mounting. Secured to the shaft of motor 38 are one or more fan rotors 41. These rotors are surrounded by a fan housing 42, which has a cylindrical portion secured to a flange 45 formed on the motor. 55 Flange 45 carries an annular sealing ring 46 of resilient material, which also engages the rear end of cylindrical inner casing 25. Sealing ring 46 effects an air-tight seal between the motor and casing 25, while permitting a slight amount 60 of movement between these parts.

Motor 38 is formed with openings 47 in the forward bearing plate, and all of the air discharged from fan rotors 41 is forced to pass through these openings. The rear part of the 65 motor is formed with a single opening 48, to which is secured a conduit member 49, which may preferably be made of rubber or other flexible material. The shape of member 49 may best be seen from Figs. 5 and 6. The lower rectangular end 50 of member 49 receives a rectangular piece 51 which extends forwardly into a channel 52 formed between the bottom 55 of lower part 12 of the casing, and a member 56, shown clearly in Fig. 4. Member 56 is formed with vertical sides 75

57 and an inner convex top 58. A strip of asbestos or other heat-resisting flexible material 59 is preferably placed between the top 58 and inner casing 25. The portion of lower part 12 of 5 the casing which forms the bottom 55 of channel 52 is preferably corrugated and is shown in Figs. 4 and 11 in order to provide a maximum heat transfer surface and to stiffen the plate. The forward end of channel 52 communicates with a 10 space 60 (Fig. 5) formed in the casting 19 between the bottom of the casting and transverse wall 22. Casting 19 is formed with a forward threaded aperture 61 which also communicates with the space 60. Aperture 61 is adapted to receive a threaded end of hose 36 when it is desired to use the device for blowing purposes. Wall 22 is formed with openings 62 adjacent either end thereof, which openings communicate with a space 65 bounded by wall 22, circular part 21 15 and the outer wall of the casting. A valve member 66 is pivoted at 67 and serves to close either openings 62 on the one hand or opening 61 on the other. A spring 68 serves to normally hold valve member 66 in the position shown in Figs. 7, 8 and 20 9, so that the central part 69 of the valve member bears against the material of casting 19 surrounding opening 61, and thus serves to close the opening.

The hose 36 is provided with an extension 10, 30 which, when the hose is screwed into opening 61, presses valve member 66 to the position shown in Fig. 10. In this position the end portions 71 of the valve member bear against the lower side of wall 22 around the openings 62, and these openings are thereby closed. It will be seen that the end portions 71 of the valve member lie in the same plane, while the central portion 69 is in a plane parallel thereto but spaced somewhat therefrom.

40 Space 65 communicates with a similar space 72 bounded by casing 10, inner casing 25 and member 56. Upper part 11 of the casing is formed with a plurality of louver openings 75, which establish communication between space 72 and the atmosphere. Openings 65 are inclined as 45 shown in Fig. 1, so as to direct air discharged therethrough upwardly and away from the surface supporting the cleaner.

The dust indicator is located in a recess formed 50 in the upper part of casting 19. The indicator includes a cap-shaped member 77 secured in place within the recess by means of a member 78 having openings 79 therethrough which communicate with the space immediately outside of dust bag 26. The upper end of member 77 is formed 55 with an annular flange which receives and holds in place a piece of glass or other transparent air-impervious material 80. A visual indicating member 81 is pivoted at 82 to the bottom of the cap-shaped member 77. Member 81 comprises 60 an arcuate portion 85 adapted to be rotated underneath an opening 86 formed in the casting 19 above the glass 80. The upper convex surface of part 85 bears markings of a nature to indicate its position. A weight 87 is secured to indicator member 81 and tends to cause the member to rotate in a clockwise direction, as viewed 65 in Fig. 12, about pivot 82. Secured between the bottom of cap-shaped member 77 and member 78 70 is a flexible diaphragm 88 to the central part of which is secured a plate 89 and a flanged disc 90. A rivet or the like 91 passes through disc 90, diaphragm 88 and plate 89, and bears against a horizontal portion 92 of indicator member 81. A 75 spring 95 is retained between member 78 and

flanged disc 90, and tends to hold plate 89 in contact with the bottom of cap-shaped member 77 and to hold the upper end of rivet 91 against part 92 of indicator member 81.

Casting 19 is formed with a passageway 96 extending from recess 76 to an annular groove 97 which extends around opening 20. Flange 29 on dust bag ring 28 is formed with one or more depressed portions 98 which extend into groove 97 and are provided with openings 99, which establish communication between the space within cap 31 and groove 97. Inasmuch as the space within cap 31 is directly in communication with the interior of dust bag 26, the pressure existing within the dust bag is communicated through openings 99, groove 97 and passage 96 to within recess 76. Cap-shaped member 77 is formed with one or more openings 100 whereby this pressure is communicated to within the cap-shaped member, and acts upon the upper side of diaphragm 20 98.

The bottom of part 12 of the casing and the bottom of casting 19 are formed with downwardly extending portions 101 and runners 102 are secured to the lower ends of portions 101. 25 These runners serve to support the cleaner on the floor or the like, and permit of its being drawn easily over such surface. The upper part of the casing may be formed with a depression 103 for receiving a handle member 105. An electric switch 106 is secured within the upper part of casting 19 and is connected into the electric circuit of the motor by means of leads 107 running from the switch to the rear of the cleaner through the space 72 between casing 10 and inner casing 25. The rear or upper part 11 of the casing may be rounded, as shown at 108 in Fig. 1, and formed with a vertical fin 109 from which extends the electric conductor lead 110.

The operation of the above described device 40 is as follows:

If the hose 36 is connected to suction opening 35, as shown in Figs. 1, 2 and 5, and the motor-fan unit is operated, air will be drawn in through the hose and into the interior of dust bag 26. 45 If a nozzle or like cleaning implement 112 is secured to the end of hose 36 and passed over a dusty surface, dust will be drawn in with this air and deposited within the dust bag. The air will pass through the material of the dust bag 50 into the inlet of the fan and be discharged from the fan and pass through the electric motor 38, thereby cooling the motor. The air is discharged through opening 48 at the rear of the motor and passes through members 49 and 51 to within channel 52. From here the air passes into space 60 formed in casting 19 and through openings 62 in wall 22 into space 65. Unless the hose is screwed into opening 61, valve member 66 closes this opening and no air escapes therethrough. 55 From space 65 the air passes into space 72 formed between casing 10 and inner casing 25. From here the air is discharged through louver openings 75 in a plurality of streams to the atmosphere. 60

65 It will thus be seen that the air has passed the entire length of the cleaner after having been discharged from the motor-fan unit, and then has its direction reversed and starts to pass toward the rear of the cleaner before its passage to 70 the atmosphere. This comparatively long path of travel of the air causes the sound produced by the operation of the motor-fan unit, which sound is carried along by the air, to be deadened considerably before the air is finally discharged. 75

This results in a much quieter operation of the cleaner than would be the case if the air were immediately discharged after having passed through the motor-fan unit. The corrugations 5 in the bottom of channel 52 permit radiation of heat from the air which has been warmed by the motor, and thus prevent any possibility of overheating of the cleaner.

If it is desired to use the device for blowing 10 purposes, hose 36 is screwed into opening 61. The extension 70 on the hose presses valve member 66, against the action of spring 68, to the position shown in Fig. 10, thus closing openings 62. When the motor-fan unit is operated air is 15 drawn through opening 35, and passes as before described to space 60. From here the air passes directly into the hose and does not pass through openings 62 into space 65.

The operation of the dust indicator will now 20 be described.

The dust bag always offers some resistance to the passage of air therethrough, and hence the pressure existing within inner casing 25 and outside of the dust bag is lower than the pressure 25 existing within the dust bag. As dirt accumulates within the bag this adds to the resistance to flow, and hence the pressure drop through the bag is an indication of the amount of dirt contained therein. The low pressure outside of the 30 bag is communicated through openings 79 to the lower side of diaphragm 88. As before described, the pressure existing within the bag is communicated to the upper side of the diaphragm. As dirt accumulates within the bag, this causes an 35 increase in the difference in pressure, and hence there is a greater pressure difference acting on the diaphragm. Inasmuch as the higher pressure exists within the bag and hence on the top of the diaphragm, the diaphragm is caused to move 40 downwardly against the action of spring 95. This causes the upper end of rivet 91 to be moved away from part 92 of the indicator member 81, and weight 87 is able to cause the indicator member 45 to rotate slightly in a clockwise direction. The amount of this rotation is visible through opening 86 and when it is sufficient the operator knows that the dust bag should be removed and emptied.

In order to remove the dust bag it is only 50 necessary to unfasten clips 32 and remove cap 31. This may be done without standing the cleaner on end inasmuch as the open end of the bag is in an inclined position and the dirt contained therein will not fall out when the cap 31 is removed. The bag may be withdrawn through opening 20 in the casting 19 and emptied. In 55 replacing the bag it is preferable to start the motor-fan unit, and the suction thus produced will draw the bag into place within the cleaner. The air flow carries the closed end of the bag to 60 the right, as viewed in Fig. 5, until it strikes the closed end of cage 21. Thereafter, the difference in pressure inside and outside the bag tends to inflate it to the greatest possible extent and hence 65 tends to straighten out the bag adjacent to the open end thereof where it is somewhat curved due to ring 28 being in an inclined position. This tendency to straighten out the bag prevents the formation of folds at this point, and the folding 70 occurs further back toward the closed end of the bag.

While I have shown one more or less specific embodiment of my invention, it is to be understood that this has been done for purposes of 75 illustration only and does not constitute a limita-

tion. The scope of the invention is to be determined by the appended claims viewed in the light of the prior art.

What I claim is:

1. A casing for a vacuum cleaner including a 5 front member, a lower shell, an upper shell, said front member being formed with an inlet opening and an outlet opening, means for securing said shells together and to said front member, a dust bag in said casing, said front member having an 10 inclined wall formed with an opening, means for securing the open end of said dust bag in said opening, said lower shell having runners for mov- 15 ably supporting said casing on a surface, a flexible hose, and means for connecting an end of said 15 hose to said opening, said hose being adapted for pulling said casing around on said surface.

2. In a vacuum cleaner, a casing including a lower shell portion and an upper shell portion, a frame member extending upwardly from the side 20 of said lower shell and within said casing, a motor-fan unit supported by said frame within said casing, and means for securing said upper shell to said frame whereby said shells are held in fixed 25 relationship.

3. In a vacuum cleaner, a casing formed with a horizontally extending space for a dust bag, a dust bag formed with an open end and having a length greater than the length of said space, and means 30 for securing the open end of said bag in a position inclined with respect to the lengthwise extent of said space, whereby the axis of the bag is curved adjacent to said open end.

4. In a vacuum cleaner, a casing arranged to be supported horizontally on a substantially horizontal surface and formed with an opening in a plane inclined to the horizontal, said opening communicating with a space within said casing having a horizontal lengthwise extent, a dust bag in said space having a length greater than that of the 40 space, said dust bag having an open end, and means for removably securing said open end adjacent to said inclined opening in said casing, whereby the axis of the bag is curved adjacent to 45 said open end.

5. A vacuum cleaner including a casing having a horizontal longitudinal extent when normally mounted on a horizontal surface, said casing having an opening at one end in an inclined plane, a dust bag having an open mouth securable in said 50 opening and normally extending longitudinally of the casing, said dust bag being supported in said casing along the bottom so that the center-line of the bag is bent adjacent to the mouth thereof, a cover for securing said bag at said inclined opening, and surface contact means on said casing whereby the casing may be pulled in the line of longitudinal extent.

6. A vacuum cleaner including a casing having a horizontal longitudinal extent when normally mounted on a horizontal surface, said casing having an opening at one end in an inclined plane, a generally cylindrical dust bag having an open mouth securable in said inclined opening and normally having its axis extending longitudinally of 65 the casing, said dust bag being supported in the casing along the bottom so that the axis of the bag is curved adjacent to the mouth thereof, a cover for securing the mouth of the bag in the inclined opening, and a hose connectible to said cover for 70 delivering dust-laden air to said bag and for pulling the casing in the direction of its longitudinal extent.

7. In a vacuum cleaner, a casing, partition means dividing said casing into a first chamber, a 75

second chamber and a third chamber, said casing being formed with an inlet opening at one end thereof communicating with one end of said first chamber, and with an outlet opening at the same 5 end communicating with one end of said second chamber, the other ends of said first and second chambers being in communication, said casing being formed with a plurality of outlet openings communicating with said third chamber, said

10 partition means being formed with a passage between said second and third chambers adjacent the first mentioned outlet, means for producing flow of air through said casing, and valve means for closing said first mentioned outlet and opening 15 said passage and alternatively for opening said first mentioned outlet and closing said passage.

8. In a vacuum cleaner, an elongated casing formed of an upper shell member and a lower shell member, both of said shells having substantially flat portions, means for joining said shells in air tight relation, a motor-fan unit for creating a pressure in said casing different from atmospheric, and reenforcing means in contact with the interior of said shells serving to stiffen said shells, 20 and particularly flat portions thereof, against deformation by said pressure differences.

9. Apparatus as claimed in claim 8 characterized by the fact that said motor-fan unit is supported from said reenforcing means.

25 10. A non-circular, elongated casing for a vac-

uum cleaner of the type designed to be pulled horizontally on a supporting surface by a hose including an upper elongated shell, a lower elongated shell, said shells having flattened portions and being joined together along lines in a plane 5 disposed parallel to said supporting surface, a dust separating member within said casing, and means for supporting air-flow producing means within said casing.

11. In a vacuum cleaner, an elongated casing, 10 means for supporting said casing horizontally on a horizontal surface, said casing including at least two shells having flattened portions and open ends, said shells being joined together in air-tight relation along lines in a plane disposed parallel to 15 the lengthwise extent of said casing, an end member formed with a dust bag opening, means for securing both of said shells to said end member, a dust bag securable in said dust bag opening, and means for supporting air-flow producing means 20 within said shells.

12. In a vacuum cleaner, an elongated casing having a substantially flat portion, a motor fan unit for creating a pressure in said casing different from atmospheric, and reenforcing means 25 within and in contact with the interior of said casing serving to stiffen said casing, and particularly the flat portion thereof, against deformation by said pressure differences.

GUSTAF EINAR LOFGREN. 30
